UNITED STATES PATENT OFFICE.

GEORGE E. HAMPTON, OF PITTSBURGH, PENNSYLVANIA, ASSIGNOR, BY DIRECT AND MESNE ASSIGNMENTS, TO CENTRAL ELECTRIC TOOL COMPANY, OF PITTSBURGH, PENNSYLVANIA, A CORPORATION OF PENNSYLVANIA.

ELECTRIC DRIVE MECHANISM.

Application filed January 10, 1917, Serial No. 141,584. Renewed August 30, 1921. Serial No. 497,048.

To all whom it may concern:

Be it known that I, GEORGE E. HAMPTON, a citizen of the United States of America, residing at Pittsburgh, county of Allegheny, 5 and State of Pennsylvania, have invented certain new and useful Improvements in Electric Drive Mechanism, of which the following is a specification.

This invention relates to an electric drive 10 mechanism wherein a reciprocatory element is employed for the production of work, and is designed primarily for electric hammers, although it is to be understood that it is adapted for any purposes wherein it is 15 found applicable, and the invention has for its object to provide a drive mechanism, in a manner as hereinafter set forth, including means to set up an electric current travelling alternately through two solenoids for reciprocating an element to impact on a tool to 20 operate the latter, and said mechanism including means, associated with said element and independent of the solenoids, to add to the impact between the element and the 25 tool thus increasing the capacity of the latter in performing its function.

Further objects of the invention are to 30 provide an electric drive mechanism which is simple in its construction and arrangement, strong, durable, efficient and convenient in its operation, readily assembled, and comparatively inexpensive to set up.

With the foregoing and other objects in 35 view the invention consists of the novel construction, combination and arrangement of parts, as hereinafter more specifically described and illustrated in the accompanying drawings, wherein is shown an embodiment of the invention, but it is to be understood 40 that changes, variations and modifications can be resorted to which come within the scope of the claims hereunto appended.

In the drawings wherein like reference 45 characters denote corresponding parts throughout the several views:—

Figure 1 is a longitudinal sectional view of an electric drive mechanism in accordance with this invention and showing the adaptation thereof in connection with an 50 electric hammer.

Figure 2 is a diagram illustrating the arrangement of the circuit wires with respect to the solenoids.

Figure 3 is a section on line III—III, Figure 1.

55

Figure 4 is an end view.

Figure 5 is a diagram illustrating the circuit arrangement for an A. C. hammer.

Figure 6 is a diagram illustrating the circuit arrangement for a D. C. hammer. 60

Referring to the drawings in detail, wherein the drive mechanism is illustrated by way of example in connection with an electric hammer, 1 denotes the intermediate portion and 2 and 3 the end portions of a 65 casing formed of any suitable non-magnetic material. The intermediate portion 1 is of less diameter than either of the end portions 2, 3, and provides a handle. Each of the end portions 2, 3, is open at its outer end. Interior threads are provided, as at 4, on each end portion 2, 3.

The casing at its forward end is closed by a peripherally threaded disk 5, which engages with threads 4 of the end portion 2. 75 The inner face of the disk 5, centrally thereof, has an annular boss 6, and its outer face, centrally thereof, an annular collar 7. The disk 5 is formed with a centrally disposed opening 8 which extends through the 80 boss 6 and collar 7, and has the wall thereof threaded.

Secured at one end in the collar 7 and projecting forwardly from the disk 5, is a clamp 9, having an inset portion 10. The 85 purpose of the clamp 9 will be presently referred to.

The casing at its rear end is closed by a peripherally threaded head-piece 11, which engages with the threads 4 of the end portion 3. The inner face of the head-piece 11, centrally thereof, has a boss 12, and said head-piece 11 has a centrally disposed pocket 13, which extends through the boss 12 and opens into the end 3 of the casing. The 90 wall of the pocket 13 is threaded. The head piece 11 projects rearwardly from the end portion 3 of the casing and has formed integral therewith a hollow handle member 14.

The head-piece at one side carries a laterally extending nipple 15 which opens into the member 14, and also into a passage 16, formed in the head piece 11, at one side of the pocket 13. The nipple 15 is interiorly threaded and is closed by a peripherally threaded hollow flanged plug 16^a, the latter 100

105

engages with the threads of the nipple 15 and has secured therewith a cable 17, which encloses the leading-in-wires or conductors 18, 19, 20 and switch wires 21, 22, these latter extending into the hollow handle member 14. The wires 21, 22, are connected with the main operating switch of the device and which is in the form of a push-button 23, mounted in the member 14, operated exteriorly thereof, and which is employed for throwing the mechanism into operation.

Engaging at one end with the threads of the opening 8 and at its other end with the threads of the pocket 13, is a tube 24 of non-magnetic material. The tube 24 extends from the bottom of the pocket 13 to the collar 7, and mounted thereon, within the end portion 2, is a solenoid 25, and within the end portion 3 is a solenoid 26.

Means to provide a magnetic circuit, associated with each solenoid, is arranged in each end portion 2, 3, of the casing. By way of example said means consists of a set of magnetic cores 27 and 29, formed of laminations of U-shape, secured together and overlapping the solenoids. The means to provide the magnetic circuit associated with the solenoid 25 is indicated at 27, and extends from the boss 6, of the disk 5, to the inwardly extending flange 28 at the rear of the end portion 2. The means to provide the magnetic circuit with the solenoid 26 is indicated at 29, and extends from the boss 12 of the head-piece 11, to the inwardly extending flange 30 at the front of the end portion 3. It will be stated however, that any form of means to provide the magnetic circuits can be employed, depending upon the type of hammer or device with which the drive mechanism is associated.

Arranged within the tube 24, is a reciprocating element 31, in the form of a reciprocating core, and which is constructed of any suitable magnetic material and the purpose of which is to impact against the shank 32 of a tool 33 to operate the latter. The shank 32 extends into the tube 24, in the path of the piston. The tool 33 is detachably connected with the end portion 2, by the inset portion 10, of the clamp 9, engaging in a peripheral groove 34 on the tool 33. It will be stated however, that the tool 33 can be connected with the end portion 2 in any suitable manner.

For the purpose of increasing the impact between the piston 31 and shank 32, a helical spring 35 is employed. The spring 35 is fixedly secured to the head-piece 11 and is arranged within that portion of the tube 24 which extends into the pocket 13.

The lead 18 extends to the solenoid 25, the lead 19 to the solenoid 26 and the lead 20 to a conductor 36 which bridges the solenoids 25 and 26.

The switch wires or conductors extend

from an operating switch of a circuit making and breaking device, arranged exteriorly of the hammer, to the switch or push button 23.

In Figure 5 of the drawings which illustrates a diagram of the circuit arrangement of an A. C. hammer, A is the hammer, B a source of power connected with a circuit making and breaking device, E, F, operating switch, G switch or push-button, 18, 19 and 20 leading-in-wires or conductors, 21, 22 switch wires, 17 cable, 25 and 26 the solenoids, 31 the reciprocating core.

In Figure 6 of the drawings which illustrates a diagram of the circuit arrangement for a D. C. hammer, H denotes a two segment commutator, I operating switch, K source of power connected with commutator, J small motor, O a solid iron ring, L motor control switch connected with motor, 18, 19, 20 leading-in-wires, 25, 26 the solenoids, 31 the reciprocating core, 21, 22 switch wires, G push button.

The operation of the mechanism is as follows:—

Through the means of the circuit making and breaking device exteriorly of the hammer, the current is made to energize and de-energize the solenoids alternately; this causes an alternative attraction of the reciprocating core with respect to the two solenoids, thereby producing a reciprocatory motion of the reciprocating core. When traveling in one direction impact occurs between the reciprocating core and shank of the tool, thereby causing the latter to perform its function. When traveling in the opposite direction the reciprocating core compresses the helical spring causing energy to be stored therein, which in turn is transferred to the reciprocating core and which adds to the impact between the reciprocating core and the shank of the tool thus increasing the capacity of the latter to perform its function.

The reciprocatory motion of the core 31, is obtained in conjunction with the contractor E, Figure 5, as follows:—

Upon closing the push button switch G, the coil s, of the magnet switch F, is energized, thereby closing the circuit through conductor 20, coil 26, conductor 19, coil b, conductor 8, contacts d and g, and conductor w, back to the source of supply B. The circuit is also closed through the conductor 20, coil 25, conductor 18, coil a, conductor r, contacts f and h and conductor t, back to the source of supply B.

With the core 31 positioned as shown, owing to the impedance of the coil 25, the energy in coil a is insufficient to pull armature n into coil a, to open contact g from contact d against spring z, therefore contacts g and d will remain closed. But the impedance of coil 26, is such as to permit

of sufficient energy to pass through coil *b*, to pull the armature *n* into coil *b*, against spring *k*, closing contact *h*, on contact *e*, thereby opening the circuit through the conductor 20, coil 25, conductor 18, coil *a*, conductor *r*, contacts *f* and *h* and conductor *t*, and also closing the circuit through conductor 20, coil 26, conductor 19, coil *b*, contacts *e* and *h*, conductor *t* back to the source 10 of supply B. The core 31 is thus caused to move out of coil 25, into coil 26, increasing the impedance of coil 26, and decreasing the energy through coil *b*, permitting spring *k* to pull armature *m* out of coil *b*, thereby opening contact *h*, from contact *e*, and instantaneously closing contact *h*, on contact *f* closing the circuit through conductor 20, coil 25, conductor 18, coil *a*, conductor *r*, contacts *f* and *h*, conductor *t*, and back to the source of supply B, thereby energizing coil 25 and coil *a*.

The impedance of coil 25 is such to permit of sufficient energy through coil *a*, to pull armature *m* into coil *a* against spring *z*, 25 thereby opening contact *g* from contact *d* and instantaneously closing contact *g*, on contact *e*, and closing the circuit through the conductor 20, coil 25, conductor 18, coil *a*, contacts *c* and *g*, and conductor *w* back 30 to the source of supply B.

On the instant that coil 26 is de-energized and coil 25 is energized, the core 31 is caused to move out of coil 26 into coil 25, thereby completing the cycle. Thus it will be seen 35 that the number of oscillations of the core is limited only by its own inertia.

o and *p* of contactor E, are contact arms and *v* and *x* are fulcrums. Contactor E is shown diagrammatically and it is understood 40 that any type of contactor may be employed.

The operation of this mechanism with arrangement shown in Figure 5, depends upon the reactive effect in the various 45 circuits produced by the core 31.

What I claim is:

1. A reciprocating apparatus adapted to be supplied from an alternating current circuit, wherein a core is arranged to be repeatedly moved into and out of a solenoid and wherein an electromagnetic switch means is arranged to alternately energize and de-energize the solenoid, characterized by the fact that a winding of the electromagnetic switch is connected in circuit with the solenoid to reduce the current in the winding and open the switch when the core is moved into the solenoid to increase the reactance thereof.

2. A reciprocating apparatus operated from an alternating current circuit comprising a solenoid, a core arranged to alternately move into and out of the solenoid and to increase the reactance of the circuit when moved into the solenoid, and an electromagnetic

switch means arranged to alternately energize and de-energize the solenoid, said switch having a winding connected in circuit with the solenoid whereby when the core is moved into the solenoid the switch is opened by the increased reactance of the circuit.

3. A reciprocating apparatus operated from an alternating current circuit comprising a pair of solenoids, a core adapted to alternately move into and out of each of the solenoids and to increase the reactance of the circuit when moved into a solenoid, and an electromagnetic switch means adapted to alternately energize and de-energize the solenoids, said switch having a pair of windings each connected in circuit with a solenoid whereby when the core is moved into a solenoid the switch is opened by the increased reactance of the circuit.

4. A reciprocating apparatus operated from an alternating current circuit comprising a hollow member of non-magnetic material, a pair of solenoids mounted thereon and spaced from each other, a shiftable element of magnetic material arranged in said member and adapted to alternately move into and out of each of the solenoids and to increase the reactance of the circuit when moved into a solenoid, laminated elements partially enclosing said solenoids and each providing an independent external magnetic circuit for its associated solenoid, and an electromagnetic switch means adapted to alternately energize and de-energize the solenoids, said switch having a pair of windings each connected in circuit with a solenoid whereby when the shiftable element is moved into a solenoid the switch is opened by the increased reactance of the circuit.

5. A reciprocating apparatus operated by an alternating current circuit comprising a pair of solenoids, a reciprocatory core alternately moving into and out of said solenoids, an electro-magnetic switching mechanism, an independent conductor between each solenoid and said mechanism, said mechanism including a pair of circuit opening and closing elements each in both circuits and each actuated by the increased reactance created in a circuit when said core moves into a solenoid whereby the circuit of which the solenoid forms part is opened and the circuit of which the other solenoid forms part is closed thereby reciprocating the core.

6. A reciprocating apparatus operated from an alternating current circuit comprising a pair of solenoids, a pair of electromagnetic switches each in circuit with a solenoid and each common to both circuits, a core arranged to move alternately into and out of each of the solenoids whereby when moved into a solenoid the reactance of the circuit through said solenoid and its associated switch is increased thereby causing

said latter switch to close the circuit through the other solenoid and its associated switch and to open the circuit of which the first mentioned solenoid is a part.

5 7. In a reciprocating apparatus operated by an alternating current circuit, a reciprocating core, an electro-magnetic element acting on the core for reciprocating it, means to provide a pair of independent circuits connected with said element, and an electro-magnetic switching device including a pair of circuit closing and opening members each in both circuits and one actuated by the increased reactance created in a circuit when

said core moves in one direction to open 15 such circuit and to close the other circuit thereby shifting the core in the opposite direction to create an increased reactance in the last mentioned circuit to actuate the other member to open such circuit and to 20 close the first mentioned circuit to shift the core in the other direction.

In testimony whereof I affix my signature in the presence of two witnesses.

GEORGE E. HAMPTON.
